Des. 237,134
Patented Oct. 14, 1975

237,134

COMBINED LUNCH BOX AND RADIO

John C. Westmoreland, 627 Holcomb Road,
Dallas, Tex. 75218

Filed Feb. 19, 1974, Ser. No. 443,363

Term of patent 14 years

Int. Cl. D3—01

U.S. Cl. D7—76

FIG. 1

FIG. 2

FIG. 3

FIG. 4

FIG. 1 is a front perspective view of a combined lunch box and radio showing my new design in a partially open condition;

FIG. 2 is a side elevational view thereof in a fully open condition;

FIG. 3 is a top plan view thereof in a fully open condition; and

FIG. 4 is a front perspective view thereof in a closed condition showing the side opposite that shown in FIG. 1.

The rear and bottom of the design are substantially plain.

I claim:
The ornamental design for a combined lunch box and radio, as shown and described.
